ATTORNEY.

UNITED STATES PATENT OFFICE.

ORLANDO W. SPRATT, OF PHILADELPHIA, PENNSYLVANIA, ASSIGNOR OF
SEVEN-EIGHTHS TO OTHNIEL B. EVANS, OF SAME PLACE.

SEAL-TRAP.

SPECIFICATION forming part of Letters Patent No. 244,942, dated July 26, 1881.

Application filed March 19, 1881. (No model.)

To all whom it may concern:

Be it known that I, ORLANDO W. SPRATT, a citizen of the United States, residing in the city and county of Philadelphia, State of Pennsylvania, have invented a new and useful Improvement in Seal-Traps for Wash-Basins, &c., which improvement is fully set forth in the following specification and accompanying drawing, in which the figure is a central vertical 10 section of the trap embodying my invention.

My invention consists of a seal-trap having in its base an opening the wall whereof is turned upward to form a gutter for the sealing medium, a rising and falling valve adapted to 15 dip into the seal and envelop the top of the induction-pipe, the latter entering the chamber from below, and the eduction-pipe leading from said chamber at a point above the valve. The upper edge of the gutter forms a bearing for 20 the top flange of the induction-pipe, which is passed through the bottom opening of the chamber formed by the wall of the gutter.

Referring to the drawing, A represents a chamber having an open bottom or base, the 25 wall *a* of which extends upwardly and forms a gutter, B, in which is placed mercury or other sealing medium.

C represents the induction-pipe, which leads from the wash-basin, sink, &c., and opens into 30 the chamber A at the base thereof; and D represents the eduction-pipe, which leads from the side of the chamber A to the sewer, &c., the upper end of the induction-pipe having a flange, *b*, which abuts against the edge of the wall *a* 35 of the gutter B for connecting and sustaining purposes.

Within the chamber A is a hollow or tubular valve, E, whose lower edge dips into the gutter B as its seat, it being noticed that the 40 top of said valve is closed, and the upper end of the pipe C projects into the valve above the edge of said gutter B, so as to be covered by the valve.

The top of the chamber is closed by means 45 of a cap, A', which is removable for the purpose of locating the pipes C D and valve E

and supplying the gutter B with the mercury or sealing medium.

The chamber A and valve E may be made of glass, and the pipes C D of metal, the proper parts being suitably packed to produce tight joints.

The operation is as follows: The water or fluid from the wash-basin, &c., enters the pipe C and raises the valve E, and, reaching the pipe 55 D, escapes from the chamber to the sewer, &c. When the flow stops the valve seeks its seat, and is thus sealed in the mercury, &c., in the gutter B, water or fluid, to the level of the lower line of the pipe D, remaining in the chamber 60 and submerging the valve, it being evident that the noxious vapors in the chamber cannot reach the induction-pipe. Should there be any sewer-gas or back-pressure from the sewer it is contained in the chamber, the pressure exerted 65 forcing the valve more firmly on its seat, thus insuring the reliability of the sealed joint and preventing the gas entering the induction-pipe and apartment.

Having thus described my invention, what 70 I claim as new, and desire to secure by Letters Patent, is—

1. The chamber A, having in its base an opening, the wall whereof is turned upwardly, forming the gutter, which contains the seal, in combination with the induction-pipe C, passed through the base of the chamber A, the valve E, dipping into the seal and enveloping the top of the induction-pipe, and the eduction-pipe leading from the chamber above said 80 valve, substantially as set forth.

2. The chamber A, having at its bottom the gutter B and the upwardly-turned part *a*, in combination with the valve E, which sets into said gutter, and the induction-pipe C, which 85 is provided on its upper end with flange *b* that rests on said part *a*, substantially as set forth.

ORLANDO W. SPRATT.
